UNITED STATES PATENT OFFICE.

HERBERT BROWN PEARSON, OF BROOKLYN, NEW YORK, ASSIGNOR TO SHIP OWNERS
RADIO SERVICE, INC., OF NEW YORK, N. Y., A CORPORATION OF WASHINGTON.

INDUCTANCE-COIL ATTACHMENT.

Application filed January 28, 1922. Serial No. 532,476.

This invention relates to an inductance coil attachment for use in connection with any electrical circuit in which inductance coils are employed, but which is especially 5 adapted for use in connection with a wireless receiving or transmitting system.

The object of the invention is to provide an attachment of this nature which is exceedingly simple in construction, efficient in 10 operation and economical of manufacture.

A further object of the invention is to provide an attachment which, due to its simplicity of construction and the combination of coils employed in connection therewith, 15 renders its use for the purposes set forth exceedingly simple and expedient and enables a most ready attachment and manipulation when used in connection with its associated circuits and instrumentalities.

20 A further object of the invention is to provide a unit assembly especially adapted for use in connection with what has now become known in the art as the Gowen inductance coil mounting unit.

25 Further objects of the invention will appear more fully hereinafter.

The invention consists substantially in the construction, combination, location and relative arrangement of parts, all as will be 30 more fully hereinafter set forth, as shown in the accompanying drawings and finally pointed out in the appended claims.

Referring to the drawings:

Figure 1 is a plan view of the attachment 35 of my invention, showing the same in operative position with reference to a standard form of receptacle or mounting therefor.

Fig. 2 is a view in side elevation of the 40 same, partially sectioned.

Fig. 3 is a view in front elevation of the same, partially sectioned.

Fig. 4 is a plan view of the same in horizontal section.

45 Fig. 5 is a similar view, largely diagrammatic, to illustrate the wiring connection employed.

Fig. 6 is a diagrammatic view showing the wiring employed in my attachment.

50 The same part is designated by the same reference character wherever it occurs throughout the several views.

A radio receiving station responsive to all wave lengths necessarily requires several

55 types of receivers for the most efficient re-

ception of the various wave lengths ranges, one type being most efficient for short waves and one or more other types being most efficient for the intermediate and longer waves. The usual practice, particularly in 60 the amateur station is to use a triple coil plug mounting, holding three of a variety of, and interchangeable, plugged coils of various inductance values to permit reception on all ranges of wave lengths. This 65 arrangement has proven satisfactory and efficient on wave lengths from approximately 600 meters to 25,000 meters, inclusive, but is inefficient for reception on the range of wave lengths below 600 meters. This type 70 of coil mounting, while illustrated herein, and will be briefly described, is the standard structure and in itself forms no part of my present invention except when used in connection with the unit of my invention. The 75 standard structure of mounting is illustrated, for example, in Letters Patent No. 1,365,170, granted January 11, 1921, to R. F. Gowen. When it is desired to receive wave lengths lower than 600 meters efficiently, it is generally necessary for the operator to resort to purchasing or building a special instrument for short wave reception 80 so that he has at least two distinct and separate equipments for efficient reception on 85 all waves.

One of the objects of my invention, when practiced in connection with radio communication, is to eliminate the necessity of the complete additional short wave instrument 90 by making use of the triple coil mounting for short waves, and having, instead of three separate plugged inductance coils (for example, as illustrated in the Gowen patent hereinabove referred to) a distinctly different and efficient short wave unit adapted to be inserted as a unit in their stead.

In accordance with my invention I provide an economical arrangement of necessary inductances in combination with a 100 multi-plug contactor to permit its use in circuit with the conventional duo-lateral or honeycomb type of triple coil mounting, and at the same time produce an efficient coordinating element which is comparatively simple and inexpensive in construction and so designed and applied as to render bulky and more costly apparatus, usually necessitated, unnecessary.

I accomplish the objects of my invention 110

by providing an inductance coil in the electrical field of force in which is located two smaller inductances each capable of being revolved in variometer fashion with respect 5 to the outer inductance, with or without energy transference relationship between the two revolving elements and a multi-plug contactor, having plugs and jacks electrically connected to its respective inductance 10 elements.

Referring to the drawings illustrating the invention, and particularly as shown in Figs. 1, 2 and 3, I have shown the table or upright type of coil mounting as illustrative. In this arrangement the mounting 15 consists of a baseboard 1 on which is mounted a suitable frame 2 generally containing three sets of plug and jack blocks generally designated at 4. One of the blocks, usually 20 the intermediate one, is stationary and the two side blocks are mounted on shafts 5 one end of which meshes with a gear 7 mounted on shaft 8 and controlled by a rotatable handle 9. This is the one standard type of 25 mounting shown and described more in detail in the Gowen patent, above referred to, and in itself forms no part of my present invention. Of course, in connection with this 30 type of mounting terminal posts 10 are provided for completion of the electrical circuit, in which coils are included. It is customary, with this type of mounting, to employ honeycomb coils provided with a block 35 containing a plug and jack connected respectively to the terminals of the coils, which plug and jack complete electrical circuit with the plug and jack of the mounting hereinbefore described. By means of the handles 9 operation with the coupling between 40 the respective coils is easily and independently obtained. As hereinbefore briefly stated, to enable operating on various wave lengths it is necessary in this type of mounting, which is universally used, to have 45 coils of varying values of inductance. The unit of my invention is especially applicable to this type of mounting and renders the same efficient for wave lengths shorter than 600 meters; and while, therefore, I do not 50 desire to be limited or restricted to this particular type of mounting, I have nevertheless, shown my invention as applied thereto, as one instance of its utility.

In accordance with my invention, I employ a body structure 20 which I find preferably to be in the form of a cylinder and of insulating material. Secured to this body structure at the front thereof, and generally 55 designed to give the same rigidity and strength, is a front piece 21, and at the back thereof is a bracket structure 22. While I do not desire to be limited or restricted in this respect, I prefer to form the bracket 60 structure 22 of hard insulating material such as wood, rubber, bakelite or the like. The

bracket structure 22 in effect forms the block of the unit of my invention and contains therein three plugs in alignment with each other, the plugs and jacks being so aligned and positioned as to cooperate respectively 70 with the plugs and jacks of the mounting piece on frame 2. Wound on the exterior of the body 20, and preferably in two sections, although in series, is one inductance coil 23, one terminal of which is connected 75 to the intermediate jack 24 of the device of my invention, and the other terminal of which is connected to the intermediate plug 25. A thin layer of insulating material 26 is wound around the two sections of the coil 23, as clearly shown, to protect the same. At the respective ends of the body 20 are mounted variometer coils designated generally at 25^a and 25^b. I do not desire to be limited or restricted to any particular type, 80 size or shape of variometer coil employed and have, therefore, merely illustrated a standard type of variometer coil, and show the same revoluble. The variometer coils 25^a and 25^b are mounted on shafts 26^a and 26^b respectively which are controlled by 85 means of knobs or handles 27 at the front of the attachment. The handle 27 may have secured thereto a graduated plate 28, if desired, to indicate visibly the adjustment 90 given the variometer relative to a fixed point on the frame 21. The rear end of shafts 26^a and 26^b of the variometers are provided with pigtails 29^a and 29^b respectively 95 to the plug and jack 30, 31, respectively of the block 22. With this construction, it will readily be seen that either of the variometer coils may be rotated relative to each other, or the fixed coil 23, and thereby effect a fine adjustment of tuning.

Of course, it is necessary to provide means for limiting the rotation of the shafts to prevent breaking the pigtails between the ends of the coil thereof and the plug and jack 30 and 31 thereof. Any standard means may be employed for this purpose, and I do not desire to be limited or restricted to any specific type thereof.

It will be seen from the foregoing that I have provided an exceedingly simple and efficient unit which, as a unit, may be inserted in the standard type of mounting, and with this single attachment, as distinguished from an entirely different equipment, I am enabled to obtain variometer adjustment and therefore enable the use thereof in connection with short wave lengths such as of the order of less than 600 meters. In addition thereto it will be apparent that I have provided a unit for short wave lengths which in itself is a highly efficient structure and which may be manufactured in varying sizes for most efficient tuning, irrespective of wave length. Likewise, while it is specifically adaptable to the 105 110 115 120 125 130

standard type of mounting of the plug and jack type, it is not necessarily, however, limited thereto, and may be mounted, as desired, irrespective of the honeycomb coil mounting set forth.

Many modifications and changes in details will readily occur to those skilled in the art without departing from the spirit and scope of my invention as defined in the 10 claims; but having now set forth the objects and nature of my invention and having shown and described a structure embodying the principles thereof, what I claim as new and useful and of my own invention, 15 and desire to secure by Letters Patent, is:

1. An inductance coil structure comprising a supporting body, a pair of spaced inductance coils supported thereby on parallel axes, a fixed coil also supported by

said body and positioned intermediate the 20 inductance coils, and provided with portions inductively associated with said inductance coils, a block also carried by said body, and plug and jack terminals for all of said coils carried by said block.

2. An inductance coil structure comprising a supporting body, a plurality of coils supported within said body on diametrical axes of said body, a stationary coil wound around said body, and inductively associated with said plurality of coils, a block also carried by said body, and plug and jack terminals for all of said coils carried by said block.

In testimony whereof I have hereunto set my hand on this 27th day of December, A. D. 1921.

HERBERT BROWN PEARSON.
